US00D904873S

(12) **United States Design Patent** (10) **Patent No.:** **US D904,873 S**
Sill et al. (45) **Date of Patent:** **** Dec. 15, 2020**

(54) **CLOSEABLE CARTON**

(71) Applicant: **Inno-Pak, LLC**, Delaware, OH (US)

(72) Inventors: **Jonathan D. Sill**, Delaware, OH (US);
Steven A. Mayer, Indianapolis, IN (US)

(73) Assignee: **Inno-Pak, LLC**, Delaware, OH (US)

(**) Term: **15 Years**

(21) Appl. No.: **29/700,670**

(22) Filed: **Aug. 5, 2019**

Related U.S. Application Data

(60) Division of application No. 29/633,123, filed on Jan. 12, 2018, now Pat. No. Des. 879,604, which is a continuation-in-part of application No. 29/573,421, filed on Aug. 5, 2016, now abandoned, which is a division of application No. 29/539,525, filed on Sep. 15, 2015, now Pat. No. Des. 774,893, which is a continuation of application No. 29/527,085, filed on May 15, 2015, now Pat. No. Des. 762,113, said application No. 29/633,123 is a continuation-in-part of application No. 29/573,599, filed on Aug. 8, 2016, now abandoned, which is a division of application No. 29/545,302, filed on Nov. 11, 2015, now Pat. No. Des. 774,896, which is a continuation-in-part of application No. 29/527,085, filed on May 15, 2015, now Pat. No. Des. 762,113, said application No. 29/633,123 is a continuation-in-part of application No. 29/604,589, filed on May 18, 2017, now Pat. No. Des. 816,480, which is a division of application No. 29/573,472, filed on Aug. 5, 2016, now Pat. No. Des. 787,314, which is a division of application No. 29/545,297, filed on Nov. 11, 2015, now Pat. No. Des. 786,663, which is a continuation of application No. 29/516,707, filed on Feb. 5, 2015, now Pat. No. Des. 774,891, said application No. 29/633,123 is a continuation of application No. 29/604,586, filed on May 18, 2017, now Pat. No. Des. 816,479, which is a division of application No. 29/573,600, filed on

Aug. 8, 2016, now Pat. No. Des. 787,316, which is a division of application No. 29/545,304, filed on Nov. 11, 2015, now Pat. No. Des. 787,313, which is a continuation-in-part of application No. 29/527,085, filed on May 15, 2015, now Pat. No. Des. 762,113, said application No. 29/633,123 is a continuation of application No. 29/615,117, filed on Aug. 25, 2017, now Pat. No. Des. 846,378, which is a division of application No. 29/566,225, filed on May 27, 2016, now Pat. No. Des. 800,546, said application No. 29/633,123 is a continuation of application No. 29/615,115, filed on Aug. 25, 2017, now Pat. No. Des. 846,981, which is a division of application No. 29/567,061, filed on Jun. 6, 2016, now Pat. No. Des. 799,955, said application No. 29/633,123 is a continuation of application No. 29/615,120, filed on Aug. 25, 2017, now Pat. No. Des. 879,603, which is a division of application No. 29/573,602, filed on Aug. 8, 2016, now Pat. No. Des. 799,317, which is a division of application No. 29/545,314, filed on Nov. 11, 2015, now Pat. No. Des. 776,522, said application No. 29/633,123 is a continuation of application No. 29/615,119, filed on Aug. 25, 2017, now Pat. No. Des. 847,626, which is a division of application No. 29/567,062, filed on Jun. 6, 2016, now Pat. No. Des. 800,548, said application No. 29/633,123 is a continuation of application No. 29/615,118, filed on Aug. 25, 2017, now Pat. No. Des. 846,379, which is a division of application No. 29/566,228, filed on May 27, 2016, now Pat. No. Des. 800,547.

(57) **CLAIM**

The ornamental design for a closeable carton, as shown and described.

DESCRIPTION

FIG. 1 is a front perspective view of a first embodiment showing a closeable carton, a new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a front perspective view of a second embodiment showing a closeable carton, a new design;

FIG. 7 is a rear perspective view thereof;

FIG. 8 is a front elevation view thereof;

FIG. 9 is a rear elevation view thereof;

FIG. 10 is a top plan view thereof;

FIG. 11 is a front perspective view of a third embodiment showing a closeable carton, a new design;

FIG. 12 is a rear perspective view thereof;

FIG. 13 is a front elevation view thereof;

FIG. 14 is a rear elevation view thereof;

FIG. 15 is a top plan view thereof;

FIG. 16 is a front perspective view of a fourth embodiment showing a closeable carton, a new design;

FIG. 17 is a rear perspective view thereof;

FIG. 18 is a front elevation view thereof;

FIG. 19 is a rear elevation view thereof; and,

FIG. 20 is a top plan view thereof.

In the drawings, the broken lines are for the purpose of illustrating portions of the closeable carton that form no part of the claimed design.
